UNITED STATES PATENT OFFICE.

WALTER C. WHITE, OF NEW YORK, N. Y.

DESIGN FOR AN EMBROIDERY-PATTERN.

48,139.

Specification for Design.

Patented Nov. 9, 1915.

Application filed September 16, 1915. Serial No. 51,103. Term of patent 3½ years.

To all whom it may concern:

Be it known that I, WALTER C. WHITE, a citizen of the United States, residing in the city, county, and State of New York, have invented a new, original, and ornamental Design for Embroidery-Patterns, of which the following is a specification, reference being had to the accompanying drawing, forming part thereof.

The figure is a plan view of an embroidery pattern showing my new design.

I claim:—

The ornamental design for an embroidery pattern substantially as shown.

WALTER C. WHITE.
